UNITED STATES PATENT OFFICE

HERBERT W. EKHOLM, OF CHICAGO, ILLINOIS, ASSIGNOR TO CHICAGO RAILWAY EQUIPMENT COMPANY, OF CHICAGO, ILLINOIS, A CORPORATION OF ILLINOIS

WHEEL STOP

Application filed September 1, 1932. Serial No. 631,373.

The invention relates to wheel stops of the type adapted to be applied to car rails at various points to engage a car wheel and prevent movement of the car along the track 5 irrespective of the functioning of the car hand brake.

The main object of the present invention is to provide a simple, economical effective stop easily applied to and removed from the 10 rail without drilling or other work on the rail and, preferably, to provide a wheel stop which will automatically tighten itself to the rail irrespective of careful application by the user and irrespective of wear or other 15 conditions which might tend temporarily to loosen the device.

In the accompanying drawings illustrating the invention—

Figure 1 is a side elevation of a simple 20 form of stop showing the traffic rail to which it is applied and a car wheel engaged by the stop.

Figure 2 is a transverse vertical section on the line 2—2 of Figure 1.

25 Figures 3 and 4 are, respectively, side and front elevations of a modification.

Figure 5 is a side elevation of another modification.

Figure 6 is a transverse section taken on 30 the line 6—6 of Figure 5.

Figures 7 and 8 are, respectively, a side view and vertical transverse section of another modification.

Figure 9 is a side view of another form 35 of the invention.

Figure 10 details an element used in the structure of Figure 9.

Figure 11 is mainly a side view but with a portion sectioned longitudinally illustrating 40 another form of the invention.

The traffic rail 1 is shown mounted on cross ties 2 in the usual manner. The stop device includes a block-like body 3 having a grooved underface 4 arranged to rest upon 45 the rail substantially throughout the length of the device. Block 3 has a forwardly facing wheel engaging surface 5 preferably provided with the same contour as the wheel 6. The rear portion of body 3 tapers down- 50 wardly and rearwardly from the wheel en-

gaging portion and includes an upwardly facing surface 7. A loop member encircles the rail and the rear portion of the body of the device and comprises a U-shaped strap 8 and a transverse key 9 extending through suitable openings provided therefor in the upper portions of the legs of the strap 8. 55

The open-ended strap is easily slipped under the rail and alongside of the block 3 whereupon key 9 may be inserted and driven home to tightly clamp the block against the rail. A cotter 10 or similar element as a pin, bolt, or rail spike holds key 9 against dislodgement and a lug 11 on body 3 prevents accidental disassembly. 60

Obviously any thrust by the wheel against the block tends to tighten the device and increase the frictional resistance to movement of the block along the rail. The lower portion of strap 8 will abut against the forward face of one of the cross ties if the frictional resistance to the movement of the block is insufficient to lock the same to the rail. 70

The form shown in Figures 3 and 4 includes a similar stop block 12 and a downwardly opening inverted U-shaped member 13 of round rod having eyes 15 formed in the lower ends of its legs for receiving a holding pin 14. The tapered surface 16 of the 75 block corresponds to surface 7 in Figure 1 and acts as a wedge to tighten the assembly of the device with the rail as wheel pressure is applied to the block. 80

Figures 5 and 6 illustrate a structure in 85 which the block body 17 has a longitudinal groove 18 in its inclined upper face and the sides of this groove are perforated at intervals as indicated at 19. A separate lug 20 90 may be positioned at various points along the block by a pin 21 passing through openings 19 and the lug. A loop member 22 encircles the block and the rail and is positioned by lug 20. 95

This construction adapts the device for application to rails of different heights and sizes, the full line showing of lug 20 and loop member 22 indicating the application to a relatively high rail and the dotted line show- 100

ing indicating the application to a rail of less height.

Figures 7 and 8 illustrate a modification of the upper cross member of a strap-like loop 5 such as is shown in Figure 1. The cross member is in the form of a bolt 23.

Figure 9 illustrates a body block 24 having a series of transverse notches 25 in its upper face which receive a rib 26 formed on 10 the lower face of the wedge-shaped key 27 passing through the sides of the strap 28. This notch and key construction also adapts the device for application to rails of different heights.

15 In Figure 11, the body 29 has an upstanding rear wall 30 threaded to receive the screw 31 which extends longitudinally of the block. A loop member 32 encircles the rail and the lower portion of block 29, passing 20 through an inclined groove 33 in the block. The inner end of screw 31 is provided with a seat 34 for the upper cross bar 35 of the loop member and by rotating screw 31 the device may be adjusted to fit rail sections of various 25 sizes.

Each of the structures illustrates a wheel engaging block having a wedge-like body extending lengthwise of the rail and provided with a simple loop for holding the device to the rail and any movement of the body along the rail under the thrust of the wheel will serve to increase the resistance of the device to such movement.

Various other forms of the invention may 35 be made without departing from the spirit thereof and the exclusive use of modified details of the construction coming within the scope of the claims is contemplated.

What is claimed is:

40 1. A wheel stop consisting of a wheel engaging element having a rearwardly and downwardly inclined wedge-like portion constructed to overlie the rail, and a loop member arranged to encircle the rail and said portion.

50 2. A wheel stop consisting of a wheel engaging element having a rearwardly and downwardly inclined wedge-like portion constructed to overlie the rail, and a loop member arranged to encircle the rail and said portion, said loop member including a wedge-like element extending transversely of the device and movable through said member to 55 reduce its effective length.

60 3. In a wheel stop, a block arranged to lie upon the top of a rail with its forward end disposed to engage a car wheel and with its top face inclined downwardly and rearwardly from said forward end, and a link member overlying said top face and constructed to underlie the rail, whereby said block will be clamped to the rail as it is moved rearwardly relative to said member.

65 4. A wheel stop comprising a block con-

structed to lie upon a car rail and to project upwardly therefrom to engage a car wheel and having a top face inclined downwardly and rearwardly from its wheel engaging face, a U-shaped member constructed to receive 70 said block and the rail between its legs, and a removable pin extending between the outer ends of the legs of said U-shaped member.

5. A wheel stop comprising a wedge-like block with its underside channeled to receive 75 the head of a rail, a U-shaped member applicable to said block and the rail upon which it rests, and a transverse wedge-like element extending through the outer portions of the legs of said member.

6. A wheel stop comprising a wheel engaging block constructed to rest on top of a car rail and having a portion inclined downwardly and rearwardly from the wheel engaging face, a loop member for encircling said 85 block portion and the rail upon which it rests, and means for holding said loop member in position on said block.

7. A wheel stop comprising a wheel engaging block constructed to rest on top of a car rail and having a portion inclined downwardly and rearwardly from the wheel engaging face, a loop member for encircling said block portion and the rail upon which it rests, and means for holding said loop member in different positions along said inclined 95 portion.

8. A wheel stop comprising a wheel engaging block constructed to rest on top of a car rail and having a portion inclined downwardly and rearwardly from the wheel engaging face, a loop member for encircling said block portion and the rail upon which it rests, and means for holding said loop member in different positions along said inclined portion, said means comprising a plurality of notches traversing said portion and adapted 100 to receive the upper cross bar of said loop member.

9. A wheel stop comprising a wheel engaging block constructed to rest on top of a car rail and having a portion inclined downwardly and rearwardly from the wheel engaging face, a loop member for encircling said block portion and the rail upon which it rests, and means for holding said loop member in different positions along said inclined portion, said means comprising an element bearing against the rear face of the top cross bar of said loop member and a device for positively moving 110 said element forwardly along said portion.

10. A wheel stop comprising a wheel engaging block constructed to rest on top of a car rail and having a portion inclined downwardly and rearwardly from the wheel engaging face, a loop member for encircling said block portion and the rail upon which it rests, and means for holding said loop member in different positions along said inclined portion, said means comprising a screw 115

threaded into a part of said block and extending longitudinally of said inclined portion and engaging the rear face of the upper cross bar of said loop member.

5 In testimony whereof I hereunto affix my signature this 25 day of August, 1932.

HERBERT W. EKHOLM.
